His Atty.

UNITED STATES PATENT OFFICE.

RAY H. MANSON, OF ROCHESTER, NEW YORK, ASSIGNOR TO GARFORD MANUFACTURING COMPANY, OF ELYRIA, OHIO, A CORPORATION OF OHIO.

CIRCUIT-CONTROLLER.

1,295,912.

Specification of Letters Patent.

Patented Mar. 4, 1919.

Original application filed May 18, 1914, Serial No. 839,217. Divided and this application filed December 13, 1917. Serial No. 207,611.

To all whom it may concern:

Be it known that I, RAY H. MANSON, a citizen of the United States, residing at Rochester, in the county of Monroe and 5 State of New York, have invented certain new and useful Improvements in Circuit-Controllers; and I do hereby declare the following to be a full, clear, and exact description of the invention, such as will enable 10 others skilled in the art to which it appertains to make and use the same.

This application is a division of my application No. 839,217, filed May 18, 1914.

My invention relates to improvements in 15 push button circuit controllers and the like, and has for its principal object the provision of a simple device of the class described, which can be easily operated and cheaply constructed. I also aim to produce a device 20 of the character described which will be operated by a slight movement of the movable member thereof, no matter at which point the power is applied thereto.

Although my device has many uses, it is 25 of especial use in controlling the warning signal of an automobile, where the driver generally operates the controller without looking at the same. In order to meet the requirements of this and other uses, it is de- 30 sirable to expose to the touch a large operative area, so that no matter where the movable member is touched, the circuit controller will be operated and the circuit closed.

Other objects of my invention and the in- 35 vention itself will be better understood from a description of a particular embodiment of the invention. In the drawing I have illustrated a particular embodiment of my invention.

40 Figure 1 is a sectional view through this embodiment of my invention.

Fig. 2 is a top plan view of the base, showing the contact carrying members with a modified form of spring 57.

45 Fig. 3 is a section through this embodiment of my invention showing the contacts caused to engage by the tilting of the button.

Referring now to the drawings and to the embodiment shown therein, at 53 is shown

the base for carrying the contact members 50 and is here made of insulating material and is cylindrical in shape. At 55 and 56 are shown the terminal parts to which the conductors 70 and 71 are connected. The screws of the parts 55 and 56 extend through the 55 base 53, and are electrically connected to the contacts 59 and 60. The terminal 56 and contact 59 are connected through a spring 57, which is bent over intermediate its ends and connected through a short limb to the 60 terminal 56. The contact 59 is mounted near the end of the other limb 58 of the spring 57.

As will be seen, particularly in Fig. 3, the spring 57 is adapted to be bent still further, until the contact 59 engages the contact 60, 65 closing the circuit controller. The stationary parts of the device are shown generally at 50 and the movable parts, at 51. The stationary part 50 includes the base and the terminals and contacts carried thereby, and 70 a casing 52, which is best made cylindrical in form. The movable member 51 consists of a push button, preferably formed of insulating material of large operating area. This button should be concentric with the stationary member, but of great area, and is shaped 75 somewhat like a mushroom or umbrella.

An annular channel 61 is cut in the under side of the member 51 and near the periphery thereof. It should be wide and deep 80 enough to permit the entrance of the edge of the cylindrical casing 52 therein when the button is either depressed or tilted. Means are provided for connecting the parts 51 and 50 together in such a manner as to permit 85 both sliding and rocking movement of the one with respect to the other, and at the same time to always retain the two parts in operative relation. As here shown, a plate 62 is connected upon the bottom of the member 51 by means of some suitable connecting means, such as screws 63, which project into the insulating material of which the member 51 is composed in the embodiment shown. This plate extends at 64 beyond the body 90 portion of the member 51, forming a peripheral flange or catch which engages the catch 65 upon the stationary member 50. This

catch is best formed by turning inwardly the top edge of the casing 52, thus forming a flange which makes an annular engagement with the top of the projecting portion 64 of the plate 62.

When the button is tilted, for example, by applying the pressure opposite the point 66, the plate fulcrums upon this catch so that the button is rocked about the point diametrically opposite 65, and the switch operated, as shown in Fig. 2, through pressure applied by a lug 80 depending from the member 51. The plate 64 is preferably made about the same diameter as the interior of the cylindrical casing 52, so that when pressure is applied to the center of the button, it will slide in the casing, and the member 80 will cause the operation of the switch by a depression of the free end of the limb 58 of the spring 57, as will be readily appreciated from the structure shown in the drawing.

At 73 is shown an electro-responsive device, here illustrated as an automobile horn, which is connected by the conductors 70 and 71 to a battery 72, thereby completing an electric circuit which is normally open at 59-60, but which, as will be seen, will be closed when the button is either tilted or depressed. The casing 52 should be securely fastened to the base 53. In the embodiment shown, this is assisted by turning up lugs 54 which bite into the insulating material of the member 53.

As will be readily appreciated by one skilled in the art, all of the parts can be conveniently and cheaply made with standard material and readily assembled without trouble or extra skill. The parts are compact and can be easily mounted in such places as on the steering posts of automobiles, or upon the underside of desks, etc. The spring 57 is, of course, tensioned to normally hold the switch contacts and the button in the position illustrated in Fig. 1 of the drawing.

The flanges 64 and 62 limit the relative separating movement of said casing and button and determine the normal position of these parts with respect to each other. It will also be seen that the spring 57 will return the button to the normal position shown in Fig. 1 when it is released after operation, no matter whether tilted or rectilinearly depressed.

In Fig. 2 the spring 57 is shown as U-shaped and bent upwardly at the link part.

I have illustrated this embodiment of my invention and these particular details to explain the invention, and not that I wish to be limited to such form and details. Many variations may be made therefrom without departing from the spirit of the invention, which is more particularly set forth in the appended claims.

I claim:—

1. In a push button circuit controller, the combination of a pair of electrical contacts normally separated but adapted to be brought in contact with each other, inclosing means for said contacts including 70 cylindrical walls and a base upon which said contacts are mounted, means to rigidly connect one of said contacts to said base, a metallic spring and means to connect one end of the spring to the base, the other end 75 of the spring being free and carrying the second contact, said spring being curved intermediate its ends and connected by one limb to the base and carrying the contact on the other limb, an annular inwardly 80 turned flange on the top of the inclosing means, a depressible, tilttable push button having a flange on its lower end within said inclosing means, said flanges having peripheral engagement with each other and means 85 carried by said button engaging the free limb of the spring whereby the spring holds the button in uppermost position and whereby the button causes the engagement of the contacts when either depressed or tilted. 90

2. In a push button circuit controller, the combination of a base, normally open contacts mounted on said base, means to rigidly connect one of said contacts to the base, a spring member curved over intermediate its ends, means to connect one of the limbs of the spring member to the base, the other limb being free, one of said contacts being carried on the free limb of said spring member, said contacts being normally 100 disengaged, inclosing means about said contacts, an annular flange on said means, a push button of large area having an annular catch thereon, loosely engaging the annular flange on said means normally 105 and permitting depressible and tilttable movement thereon, said button being slideable and tilttable in said means, a portion of the button engaging the free end of the spring and being held normally in uppermost position by said spring, said spring yielding when the button is either depressed or tilted to cause the engagement of said contacts. 110

3. In a push button circuit controller, 115 the combination of a cylindrical casing, a base of insulating material in the bottom of said casing, a stationary contact eccentrically mounted on the top of said base, a terminal electrically associated with said contact, a spring contact connected at one end to said base on the top thereof and opposite the first contact, said spring being looped back upon itself and extending to the other contact and normally disengaging 120 the same, an inwardly turned flange on the top of the casing, a push button having means on its underside engaging the under-

side of said flange, the edges of the button extending beyond and down over the top of the casing and a projection on the bottom of the button normally engaging said spring 5 contact between the ends thereof and depressed straight down to cause said contacts to engage. In witness whereof, I have hereunto signed my name this 8th day of December, 1917.

RAY H. MANSON.
